TIRE

William F. Billingsley, Silver Lake, Ohio, assignor
to The B. F. Goodrich Company, New York,
N. Y., a corporation of New York

Application September 30, 1950, Serial No. 12,417

Term of patent 14 years

(Cl. D90—20)

To all whom it may concern:

Be it known that I, William F. Billingsley, a citizen of the United States of America, residing at Silver Lake, in the county of Summit and State of Ohio, have invented a new, original, and ornamental Design for a Tire, of which the following is a specification, reference being had to the accompanying drawing, forming a part thereof.

In the drawing, the figure is a perspective view of a tire embodying my new design.

I claim:

The ornamental design for a tire, as shown.
WILLIAM F. BILLINGSLEY.
